US00D785360S

(12) **United States Design Patent** (10) **Patent No.:** **US D785,360 S**
Rawls-Meehan (45) **Date of Patent:** **** May 2, 2017**

(54) **DECK-ON-DECK ADJUSTABLE BED**(71) Applicant: **ASCION, LLC**, Bloomfield Hills, MI (US)(72) Inventor: **Martin B. Rawls-Meehan**, Franklin, MI (US)(73) Assignee: **ASCION, LLC**, Bloomfield Hills, MI (US)(***) Term: **15 Years**(21) Appl. No.: **29/531,712**(22) Filed: **Jun. 29, 2015****Related U.S. Application Data**

(63) Continuation of application No. 29/446,425, filed on Feb. 22, 2013, now Pat. No. Des. 720,553, which is a continuation of application No. 13/750,934, filed on Jan. 25, 2013, now Pat. No. 9,173,793.

FOREIGN PATENT DOCUMENTS

GB	920643 A	3/1963
JP	3068744 B2	7/2000

(Continued)

Primary Examiner — Cathron Brooks(74) *Attorney, Agent, or Firm* — Dinsmore & Shohl LLP(57) **CLAIM**

The ornamental design for an deck-on-deck adjustable bed, as shown and described.

DESCRIPTION

FIG. 1 is a perspective view of a deck-on-deck adjustable bed design; and,

FIG. 2 is a side perspective view of the design of FIG. 1. The broken lines in the drawings illustrate portions of the adjustable bed that form no part of the claimed design.
